UNITED STATES PATENT OFFICE.

JOHN HEESEN, OF TECUMSEH, MICHIGAN, ASSIGNOR TO HEESEN BROTHERS & CO., OF SAME PLACE.

HOG-RINGING TOOL.

SPECIFICATION forming part of Letters Patent No. 226,915, dated April 27, 1880.

Application filed February 2, 1880.

To all whom it may concern:

Be it known that I, JOHN HEESEN, of Tecumseh, in the county of Lenawee and State of Michigan, have invented certain new and useful Improvements in Hog-Ringing Tools, of which the following is a specification.

My invention relates to an improvement in implements for inserting rings in the snouts of swine.

It consists, first, in a pair of pinch-tongs, with each limb of the instrument having two jaws of different size lying in different longitudinal planes, so that when the two members are put together there are two sets of nipper-jaws, one upon the right and the other upon the left of the pivotal plane, one being adapted in size for ringing hogs and the other for smaller swine or pigs.

A second part of my invention consists in providing a guard or gage upon one of the pincher-jaws to prevent the prongs of the jaws from reaching too far over the snout of the swine and inserting the ring too deep, grasping the flesh instead of the gristle of the snout, all of which will be more fully understood by reference to the accompanying drawings and description thereof, in which—

Figure 1 is a plan view of my invention, and Fig. 2 is an elevation of one of the duplex jaws.

A represents one of the jaws; a, the handle or lever. B represents the opposite jaw, and b its handle or lever.

C represents the outer prong of the larger pincher, and c the inner jaw of the same. D represents the inner prong of the smaller set of pinchers, and d the outer prong of the same.

F represents a flange upon the outer surface of the duplex jaw B, and L represents a corresponding flange on the outer surface of jaw A. Between these two flanges are formed shoulders or ledges O, one on the inner side of each flange, for the reception of the blank or ring R. G represents the flange of jaw A.

The flanges F and G project up farther than their opposite flanges L and L', and form a guard or stop to prevent the prongs of the

pinchers from projecting too far over the animal's snout.

E represents the pivot of the jaws A B. H and I represent offsets on the face of the jaws A B, the depth of which corresponds with the depth of the groove and thickness of the flange on one side of the groove.

H' represents a second offset, in which flange L moves in the opening and closing of the jaws. A corresponding offset is made for the flange L' on jaw d.

R represents a blank, partially bent, held in the jaws of the pinchers, ready for insertion into the snout.

J J represent stops placed on the handles a b to prevent the closing of the end of the jaws, as it is desirable to have them some distance asunder to prevent the pinching of the snout and to insure the lapping and joining of the ends of ring R in inserting the same.

It is obvious that, while I have shown each of my features of invention all embodied in one instrument, one or more of the same may be omitted without affecting the operation of the remaining improvements.

It is also obvious that flanges might be provided on the prong C opposite the flange F, or that the faces of the prongs may each be grooved to form recesses for the blank or ring, and still embody the features specified in my first and second claims; but this modification is unnecessary, as the form shown is sufficient to securely hold the blank.

I have shown my improvement in the form adapted for the insertion of flat blanks or rings; but it is obvious that slight modifications may be made to adapt the instruments to the use of any desired form or shape of ring.

I claim—

1. An instrument for ringing swine consisting of two limbs pivoted side by side, each limb having duplex jaws of different size, the jaws on one coacting with those on the other limb to produce two sets of nipper-jaws of different size, substantially as described.

2. In an instrument for ringing swine, the projection of the flanges near the center be-

tween the prongs of the jaws, forming a guard or gage, substantially as and for the purpose set forth.

3. In an instrument for ringing swine, the combination of the two jaws A B, pivoted together side by side and each provided with a flange projecting from one of its sides, and an intermediate lateral shoulder or ledge for

receiving and holding the blank or ring, substantially as described.

In testimony whereof I have hereunto set my hand this 30th day of January, 1880.

JOHN HEESEN.
